UNITED STATES PATENT OFFICE.

AXEL ECKBERG AND GUSTAF OHRSTROM, OF JAMESTOWN, NEW YORK.

FOLDING BED-SEAT.

1,173,939.

Specification of Letters Patent. Patented Feb. 29, 1916.

Application filed August 22, 1914. Serial No. 858,033.

To all whom it may concern:

Be it known that we, AXEL ECKBERG, a citizen of the United States, and GUSTAF OHRSTROM, a subject of the King of Sweden, both residing at Jamestown, in the county of Chautauqua and State of New York, have invented certain new and useful Improvements in Folding Bed-Seats, of which the following is a specification.

10 Our invention relates to folding furniture and more particularly to improvements in folding bed-seats.

15 The primary object of our invention is the provision of a folding bed-seat which is durable in construction, simple to operate, and which contains few parts so that the possibility of wear on the moving parts when folding or extending the seat is reduced to the minimum.

20 Another object of our invention is the production of a yielding seat or supporting member which will not sag from use, and in which the stretches of webbing usually employed in articles of furniture of this type 25 are at all times retained in flattened condition.

Another object of our invention is to provide spring supporting devices for the seat member having integral connector parts 30 whereby the separate connections usually employed are dispensed with and consequent wear avoided.

Another object of our invention is the provision of diagonal webbings interwoven with 35 cross or transverse webbings in such a manner that the latter are at all times retained in flat condition, and to so support and lace or thread the diagonal webbings through supporting elements that they are themselves at 40 all times retained in flat condition, the diagonal and cross webbings providing a flat support for the bedding and body.

Other objects of our invention are, to connect the folding or collapsible side supporting members of the seat in such a manner 45 that they cannot spread under weight supported thereby, and to otherwise improve on folding articles of furniture now in use.

To these ends the invention consists in the 50 novel features of construction, and in the arrangement and combination of parts to be hereinafter described and particularly pointed out in the subjoined claims.

In the drawings,—Figure 1 is a side elevation 55 of a folding bed-seat embodying my invention. Fig. 2 is a plan view of the same.

Fig. 3 is an enlarged cross section taken on line 3—3, Fig. 1. Fig. 4 is a side elevation of the bed-seat as it appears when folded. Fig. 5 is a detached perspective view of one of the spring supporting devices for the webbing. Fig. 6 is a perspective view of a modified form of spring supporting device.

Referring now to the drawings in detail, like numerals of reference refer to like parts in the several figures.

The reference numeral 7 designates the folding or collapsible side members of the bed-seat, each of which is preferably constructed of two sets of parallel wooden or metallic bars 8 arranged diagonally, the bars of each of said sets being adapted to cross those of the other, as at 9, and have their upper ends meet the upper ends of said other set, to which they are pivotally secured, as at 10. At their points of crossing the bars of both sets are also pivotally connected together. While the exact arrangement and connection of these side bars provide collapsible members which are capable of supporting heavy weights without unduly straining the connections, it is nevertheless our intention that such arrangement and connection may be changed without departing from our invention, as it is possible to construct collapsible side members otherwise than herein shown and described which would be capable of use in connection with other parts of our bed-seat, as various forms of articles constructed to fold accordo-like are now in use. We nevertheless consider the exact arrangement and connection of bars constituting the folding side members of considerable importance, due to the sustaining qualities of the same. At intervals along the length of these folding side members, dove-tailed transverse grooves 12 are formed in several of the bars near their upper and lower ends, in which grooves are entered the flaring ends 13 of transverse connector rods 14, said rods serving to tie the folding side members securely together and retain them in proper position relatively.

The connections of these connector rods to the bars 8 enable us to dispense with securing bolts, which oftentimes in present constructions become loose and permit the folding side members to spread when the seat supports a load.

15 designates a supporting member which comprises yielding supporting devices 16 secured to the upper ends of the side members

7 and webbings 17, 18, spanning the space between said supporting devices at opposite sides of the seat. The supporting-devices 16 are arranged in two series, one series being secured to the top of each collapsible side member and the supporting-devices of one series being directly opposite those of the other. In preferred form, each supporting-device is constructed of a single piece of wire 10 coiled approximately midlength into spiral-spring form, as at 19, and extended in opposite directions from said spring to provide at one end a combined pivot and securing-member 20 and at its other end a connector 21. The securing-member 20 is formed by rebending the wire into U-formation, the extremity of the wire at this end being thrust through registering openings in the upper ends of two meeting bars 8 and serving as 20 a pivot connection for said bars, the extremity being suitably headed if desired, as at 22, so as to prevent withdrawal from said bars. The connector 21 is preferably formed by bending the wire into triangular loop-form, through which the webbings 17, 18 are laced or threaded. The opposite supporting-devices are connected together by stretches of cross webbings 17, the webbing being passed around the transverse or base 30 portion 23 of the triangular loops 21 and riveted, sewed, or otherwise secured thereto. Two stretches of diagonally-arranged webbings 18 are provided, the ends of the same being riveted or otherwise secured to the 35 two end stretches of cross webbings, as at 24, each stretch of diagonally-disposed webbing being laced or threaded through alternate loops at opposite sides of the seat and passed above and beneath adjoining cross webbings 40 at opposite sides of the seat. The two stretches of diagonal webbings cross each other at points between the cross webbings, each stretch passing alternately above and beneath the other; thus keeping said diagonal webbings stretched their full width and preventing them turning edgewise when the seat 45 is extended for use as a bed. The spring supporting-devices 16 and the webbings 17, 18, constitute an elastic, even and smooth 50 surface for the occupant's body.

In the modification shown in Fig. 6, the supporting-device is formed in three pieces, one being a coil-spring 25 having one end of the wire forming the same bent into hook 55 form, as at 26, and the other end being extended a trifle from the spring, as at 27, and its end bent into hook form, as at 28. The hook 26 is adapted to engage a triangular loop 29 through which the webbings 17, 18, are 60 to be laced and the hook 28 is passed through an opening formed in a metallic securing member 30 bent at a right angle, as at 31, and adapted to be secured to the upper ends 65 of the bars 8.

65 The constructions described provide a

spring-supported triangular loop, the apex of which has continued or secured thereto the yielding member of the supporting device, and the base or transverse bar serves to hold the webbings securely thereto in flattened condition at all times, thus avoiding turning of these webbings edgewise. A very important feature of these webbings lies in the manner in which the diagonally-disposed webbings are arranged with reference to the 70 transverse webbings, attention being invited to the fact that the ends of the transverse webbings have lying against their opposite faces the oppositely-directed portions of the diagonally-disposed webbings, each of said 75 diagonally-disposed webbings passing above and beneath one of the ends of alternate transverse webbings and beneath and above the opposite ends of the intermediate transverse webbings, and when the diagonal webbings are properly stretched they will retain the transverse webbings in flattened condition by reason of their passing through the widened inner ends of the triangularly 80 formed loops.

Although the constructions herein shown and described are believed to be those most practicable for the purpose intended, it is apparent that changes in minor details of construction may be resorted to without departing from our invention or sacrificing any of the advantages thereof; also that certain parts of our invention may be used without others without change of functions.

Having thus described our invention, 100 what we claim is,

1. In a folding article of furniture, the combination of two spaced collapsible side members, a series of loops yieldingly connected to the tops of said side members, 105 transversely-disposed stretches of webbing connecting said two series of loops in pairs, and two stretches of diagonally-disposed webbings laced through said loops and lying respectively above and beneath the ends of 110 said transverse stretches of webbing.

2. In a folding article of furniture, the combination of two spaced collapsible side members, yielding supporting devices including loops connected to the tops of said 115 side members, said supporting devices being arranged in two series with the devices of one series directly opposite those of the other, transverse stretches of webbing connected to the loops of opposite supporting devices, and two stretches of webbing laced through said loops and directed diagonally back and forth from one series of supporting devices to the other, said diagonally-directed stretches of webbing lying in contact with the ends of said transverse stretches of webbing above and beneath the same and crossing each other at points 120 between said transverse stretches of webbing.

3. In a folding article of furniture, the combination of collapsible side members spaced rigidly from each other, said side members comprising pivotally connected bars, a supporting member extending from side member to side member and comprising supporting devices formed of wire coiled medially into spring-form and having the wire at one end extended from the 10 spring to provide a U-shaped securing portion and the other end of the wire bent into loop form, said U-shaped securing portions being fastened to the upper ends of said bars to pivotally connect said ends, and 15 stretches of webbing passed through the loops at opposite sides.
4. In a folding article of furniture, the combination of two collapsible side members spaced rigidly one from the other, said 20 side members comprising a series of crossed bars pivotally connected together with the upper end of each bar meeting another at a common point and provided with registering openings at such points, and a supporting 25 member extending from the upper ends of the bars of one side member to the upper ends of those of the other, said supporting member comprising supporting devices having their outer end portions passed 30 through the registering openings at the meeting points of said bars to serve as pivots for the same and being provided with loops at their opposite ends, and stretches of webbing connected to said loops.
- 35 5. In a folding article of furniture, the combination of collapsible side members, supporting devices secured to the tops of said side members and extending inwardly therefrom, each of said supporting devices 40 having a loop at its inner end, transversely-disposed stretches of webbing connecting opposite loops, and two stretches of diagonally-disposed webbings passed through
- said loops and extending above and beneath the ends of said transversely-disposed 45 stretches of webbing, the end of said two stretches of diagonally-disposed webbings being secured to the end stretches of transversely-disposed webbings.
6. In an article of furniture, the combination of the side members and a supporting member constructed of webbing attached to the tops of said side members, said supporting member comprising transversely-disposed stretches of webbing and 50 two stretches of diagonally-disposed webbings arranged to lie in contact with the upper and under sides of said transversely-disposed webbings at opposite ends of the latter, thus preventing the turning edgewise 55 of said transversely-disposed webbings.
7. In an article of furniture, the combination of the side members and a supporting member constructed of webbings, said member comprising yielding supporting devices secured to said side members at their outer ends and having triangular loops at their inner ends, transversely-disposed webbings connecting the loops at opposite sides 65 of said supporting member, and diagonally-disposed stretches of webbing threaded through said loops and lying in contact at opposite ends of said transverse webbings, said diagonally-disposed stretches of webbing being arranged to pass underneath 70 and above opposite ends of each transversely-disposed stretch of webbing to prevent turning of the latter edgewise. 75

In testimony whereof we affix our signatures in presence of two witnesses.
